[57] CLAIM

The ornamental design for a combined cake and pie cutter, substantially as shown and described.

DESCRIPTION

FIG. 1 is a perspective view of the top, front, and left side of a combined cake and pie cutter showing the first embodiment of my new design;

FIG. 2 is a perspective view of FIG. 1 showing the bottom rear and right side thereof;

FIG. 3 is a perspective view of the bottom rear and right side of a second embodiment of my new design;

FIG. 4 is a perspective view of the design of FIG. 3 showing the top front and left side thereof; and

FIG. 5 is a cross-sectional view on an enlarged scale of the blade of the design shown in FIGS. 1—4 taken along line 5—5 of FIG. 3.

FIG. 1

FIG. 2

FIG. 5

FIG. 3

FIG. 4
